UNITED STATES PATENT OFFICE.

THOMAS A. McCALL, OF CLEVELAND, OHIO, ASSIGNOR TO THE AUTOMATIC TYPE-WRITER COMPANY, OF CLEVELAND, OHIO, A CORPORATION OF OHIO.

MECHANISM FOR FEEDING PAPER TO TYPE-WRITERS.

1,029,206.

Specification of Letters Patent.

Patented June 11, 1912.

Original application filed March 19, 1908, Serial No. 422,033. Renewed April 22, 1909, Serial No. 491,602. Divided and this application filed September 24, 1909. Serial No. 519,415.

To all whom it may concern:

Be it known that I, THOMAS A. McCALL, a citizen of the United States, residing at Cleveland, in the county of Cuyahoga and State of Ohio, have invented a certain new and useful Improvement in Mechanism for Feeding Paper to Type-Writers, of which the following is a full, clear, and exact description.

10 The object of this invention is to automatically feed sheets of paper to automatically operated typewriters.

In the precise form in which the invention is shown taken in connection with the mechanism shown for operating it, it is especially adapted for use with automatic typewriter operating mechanism which forms the subject matter of my pending application No. 491,602, filed April 22, 1909, 20 (the same being a renewal of an application No. 422,033, filed March 19, 1908,) of which this application is a division. It will be understood, however, that the invention as defined by the appended claims is not restricted to the specific construction shown, nor to use in connection with the herein unclaimed mechanism shown in said original application.

30 In the drawing, Figure 1 is a side elevation showing the mechanism in which the present invention is embodied and so much of an automatically operated typewriter as shows the operative relation between said mechanism and the typewriter. Fig. 2 is a 35 front elevation of the invention and corresponding parts of the typewriter and its operating mechanism. Fig. 3 is an inside view, of the mechanism for guiding the suction cups.

40 Referring to the parts by letters, 87 represents a standard which carries at its upper end a receptacle 88 which is disposed at a slight inclination. This receptacle is a box-like structure having an open front side, 45 and it is provided for and adapted to the holding of a pack of paper sheets P, which the mechanism to be described is to feed, sheet by sheet, to the paper holding mechanism of a typewriter. The receptacle as 50 shown is pivoted to the standard 87 and may be swung into any desired angular position and there fixed by a set screw 89. Pivoted mounted upon said receptacle is a shaft 90 having arms 91 fixed thereto.

55 A tube 92 carrying suction cups 93 ex-

tends across the receptacle 88 near the lower part thereof. This tube is moved in right lines toward the pack of paper in said receptacle, and then away from the same for purposes to be presently described. In 60 order that the tube may be so moved the following mechanism is employed: Brackets 93^a are fixed to the two outer suction cups. A rod 86, which is parallel with the tube 92, passes through these brackets, and is rigidly 65 fixed thereto. This rod passes through slots 91^a in the arms 91. Upon the ends of this rod are the rectangular guide blocks 85 which slide in guideways 84 fixed to the sides of the receptacle 88. It is clear therefore that when the rock shaft 90 is rocked 70 the suction cups will move either toward and against the top sheet in the receptacle or away from the same, and will move in lines at right angles to the plane of said top 75 sheet.

94 represents a suction pipe which communicates with the tube 92 and extends to and is connected with a pneumatic cylinder 95. This cylinder is fixed in position and contains a piston 96,—the piston rod 97 of which extends upward and is pivotally connected with an arm 99 fixed to the shaft 90. A coil spring 95^x is connected at its upper end with a fixed bracket 95^x while 85 its lower end is connected with said piston rod, wherefore the spring acts to draw the piston up out of its cylinder. A second flexible tube 94^x is connected with the opposite end of the pipe 92 to that to which 90 the pipe 94 is connected, and this tube 94^x is connected with a valve casing 9 which is also connected by means of a pipe 7 with an air exhausting device of any suitable construction. The valve casing is internally 95 cylindrical, and it contains a cylindrical valve 10 wherein is a port 10^a through which the pipe 94^x may be placed in communication with the pipe 7, and a relief port 10^b through which pipes may be 100 placed in communication with the atmosphere. This valve has connected to it, on opposite sides of its axis, the two links 13 and 14, which links at their upper ends are connected with two levers 15, 15^a, mounted 105 side by side on a common axis. The other ends of these two levers lie close to a constantly rotating cylinder 28, in the periphery of which are annular recesses wherein are pivoted a plurality of triggers 29. 110

These triggers may be retracted into said recesses or may project therefrom so as to engage with said levers. A perforated strip 35 which is to control the operation 5 of the typewriter and its associated parts runs over this cylinder and is driven, belt-like, thereby in the direction indicated by the arrow in Fig. 1. Adjacent to the cylinder is an electro-magnet 32 which is constantly energized. The triggers are made 10 of iron or steel, and the attraction of the magnet tends to swing them out of the recesses in which they may lie into operative position. The unperforated part of the paper strip prevents such outward action,— except that whenever a perforation in the paper comes opposite one of said triggers the magnet will draw the trigger through the perforation, and the trigger will then engage the associated lever and rock it. If it be the lever 15 connected with the link 14 which is rocked the valve 10 will be turned so as to establish communication between the air exhausting device and the 25 tube 94^a. Air will thereby be withdrawn from tube 92 and from the cylinder 95. The piston 96 will be drawn down and thereby the shaft 90 will be rocked in the direction which causes the arms 91 to swing outward. Previously to so swinging they had occupied a position in which the suction cups 93 had been resting against the top sheet of paper in the receptacle 88. When the air was exhausted and was withdrawn from tube 92 the top sheet of paper 30 was drawn by the suction against said suction cups so that when, by the movement of the piston as described, the arms 91 were swung to the position shown in Fig. 1, the top sheet of paper was carried with it. The lower edge of this paper is carried out of the receptacle 88 and directly over a guide tube 86. When the parts have reached this position another perforation in the perforated strip will allow the projection of a trigger associated with the lever 15^a which trigger will strike the lever and rock it, thereby turning the valve 10 to a position such as will bring the relief port 10^b there- 40 in in communication with the tube 94^a. Air will rush in to said tube, and into the tube 92, and into the cylinder 95 with the result that the paper will be released by the suction cup and will fall down into the 45 guide tube 86 by which its lower edge is guided between two rolls 120 and 193 on the typewriter carriage. When thereafter said rolls are turned either by hand or by suitable mechanism, this paper will be 50 drawn between them into proper position to receive the type impression. The described turning of said valve will cause the lever 15 to be rocked back to its normal position. This will withdraw the trigger 108, and thereupon spring 101 will rock 55 rock-shaft 90, and the suction cups will again be moved against the top sheet of paper in the receptacle.

Having described my invention, I claim:

1. In combination with the paper holding mechanism of a typewriter, a paper receptacle, pneumatically operated mechanism for transferring paper sheet by sheet from said receptacle to said paper holding mechanism, a valve controlled conduit connected with the pneumatically operated mechanism, a lever operatively connected to said valve, a rotating member, a plurality of dogs pivoted upon said member, means causing said dogs to engage with the lever, 75 and a perforated strip passing between the dogs and the lever and controlling their engagement with the lever.
2. In combination with the paper holding mechanism of a typewriter, a tube, suction cups connected therewith, guides compelling the movement of said cups in right lines toward and from the paper in said receptacle, a rock shaft having slotted arms, devices connected with the cups and projecting into the slots in said arms, means for rocking said rock shaft, a valve controlled conduit which includes a flexible pipe connected with said tube, and mechanism for operating the valve in said conduit. 85
3. In combination with the paper holding mechanism of a typewriter, a paper receptacle, a rock shaft, a tube carrying suction cups, mechanism operated by the rock 90 shaft for moving said tube and suction cups toward and away from the paper in said receptacle, two flexible tubes connected with opposite ends of the tube carrying the suction cups, a valve casing intermediate 95 of said flexible tubes and an air exhausting mechanism, a cylinder with which the other flexible tube is connected, a piston in said cylinder, mechanism through which said piston operates said rock shaft, a valve 100 in said valve casing, and means for operating said valve. 105

In testimony whereof, I hereunto affix my signature in the presence of two witnesses.

THOMAS A. McCALL.
